Attorney

UNITED STATES PATENT OFFICE.

ROBERT J. McCLENNY, OF ST. LOUIS, MISSOURI, ASSIGNOR TO NU-WAY BARREL AND MACHINERY CO., INC., OF ST. LOUIS, MISSOURI.

METHOD OF MANUFACTURING COLLAPSIBLE BARRELS.

Application filed December 3, 1923. Serial No. 678,361.

To all whom it may concern:

Be it known that I, ROBERT J. McCLENNY, a citizen of the United States, residing in the city of St. Louis and State of Missouri, have invented certain new and useful Improvements in Methods of Manufacturing Collapsible Barrels, of which the following is a specification.

This invention relates to a method of manufacturing collapsible barrel bodies, and has for its object to provide, in a manner as hereinafter set forth, a method for expeditiously and inexpensively manufacturing collapsible barrel bodies of a form capable of being compactly nested when shipped in quantities, and further of a form which can be quickly arranged and detachably secured in barrel shape to be employed for shipping purposes.

20 To illustrate the construction of the body of the barrel as it appears at the completion of the several steps of the method, reference is had to the accompanying drawings in which:—

25 Figure 1 is an elevation of the body portion of a collapsible barrel illustrating the same at the completion of the first and second steps of the method.

30 Figure 2 is a like view illustrating the body portion of the barrel at the first, second and third steps of the method.

Figure 3 is a similar view, illustrating the barrel body at the first, second, third and fourth steps of the method.

35 Figure 4 is a fragmentary view, in section, illustrating the body of the barrel extended and disconnected.

Figure 5 is a fragmentary view, in section, of the barrel body collapsed.

40 In carrying out the method of manufacturing a collapsible barrel body, in accordance with this invention, the desired number of staves from which the body of the barrel is to be formed, is arranged in parallel relation and the staves are connected together by two lengths of wire secured to the outer face thereof, and each length of wire is arranged to one side of the transverse center of the staves. The staves are indicated at 1 and

45 the lengths of wire at 2, 3, and the said lengths of wire are termed a pair of spaced inner flexible securing members and each of which is of a length to have both end terminals thereof project beyond the outer staves

55 of the series or number of staves which are

employed to form the body portion of the barrel. The projecting end terminals of the member 2 are indicated at 4, 5, and the projecting end terminals of the member 3 are indicated at 6, 7. The member 2, as well as the member 3, is secured to the outer face of the staves 1, throughout, by closely arranged staples 8, which are forced through the staves and have their inner ends clenched, as at 9, whereby the members 2, 3, as well as the staples 8, are fixedly secured to the staves.

50 After the staves 1 have been secured in parallel relation through the medium of the members 2 and staples 8, the connected series of staves is positioned in a former machine to shape the connected staves in the form of a barrel body, as illustrated in Figure 1 and with the end portions 4, 5, 6 and 7 disconnected from each other.

55 Prior to the removal of the shaped body 10 from the former machine, each end of the body 10 has removably mounted thereon a hoop or band, as indicated at 11, 12, whereby the body portion 10 will be maintained in 60 the form as shown in Figures 1 and 2.

65 The formed body 10, with the hoops or bands 11, 12, on the ends thereof, is removed from the former machine and has secured to the outer face thereof two lengths of wire 13, 14 and which are termed outer flexible securing members. The securing of the outer flexible members to the formed body 10, is carried out while the body 10 has arranged on the ends thereof the hoops or bands 11, 12. The member 13 is secured to the body 10, in advance of the securing of the member 14, and the member 13 is positioned in close proximity to the hoop 11 while the member 14 is positioned in close proximity to the hoop 12, and after the members 13 and 14 are secured to the body 10, the latter is as shown in Figure 3.

70 Each of the members 13 and 14 is of such length, after being secured to the body 10, as to provide free terminal portions which project from the body 10, and the free terminal portions for the member 13 are indicated at 15, 16, and for the member 14 at 17, 18.

75 The member 13, as well as the member 14, is secured to the staves 1, throughout the outer face of these latter, by closely arranged staples 19 which are forced through the staves 1 and have their inner ends 80

clenched in the same manner as the staples 8.

After the outer flexible securing members 13, 14 have been secured in position, the hoops 11, 12 are removed from the ends of the formed body 10, so that the latter can be collapsed, as shown in Figure 5.

When it is desired to maintain the formed body 10 in closed position, that is to say, for the purpose of connecting the outer end 10 staves of a series of staves together, the end portions 4, 5 are twisted together, the end portions 6, 7 are twisted together, the end portions 15, 16 are twisted together, and the end portions 17, 18, are twisted together, or if desired, the end portions 4, 6, 15 and 17 can be secured to the stave 19 which abuts against the stave 20, and the end terminal portions 5, 7, 16 and 18 can be secured to the stave 20 which abuts against the stave 19. Preferably the end portions 4 and 5, 6 and 7, 15 and 16, and 17 and 18 are twisted together whereby the body portion is detachably secured in closed position and by untwisting the end terminal portions the collapsing of the body portion can be had. The staves which provide the body portion of the barrel, have their inner faces chamfered near each end for the reception of the barrel heads.

For maintaining the barrel body closed, the hoops 19 and 20 may be employed, and when the barrel bodies are shirred, each body is accompanied by a pair of detached hoops.

The former machine which sets the staves in the position as shown in Figure 1, can impart any desired bilge thereto.

The foregoing method provides for the expeditious manufacturing of barrel bodies, as well as strong, durable and inexpensive collapsible barrel bodies, and it is thought that the many advantages of the method as herein set forth can be readily understood, and although the preferred steps of the method is as described, yet it is to be understood that changes can be had therein which will fall within the scope of the claims hereunto appended.

What I claim is:—

1. A method of manufacturing a collapsible barrel body comprising the positioning of a series of barrel staves in flat sidewise relation, securing to the outer face of said arranged staves near their transverse centers thereof a pair of spaced inner flex-

ible connecting members of a length to project from said outer stave of each series, shaping said connected series of staves into a barrel body with the projected ends of said members disconnected, applying a removable holding element to each end of said body for temporarily securing it in shaped position, then securing to the outer face of said body portion shaped barrel body in proximity to each of said holding elements an outer flexible connecting member having free end terminal portions extended from said body, and then removing said holding elements to permit of the collapsing of said barrel body. 70

2. A method of manufacturing a collapsible barrel body comprising the arranging of a series of barrel staves in flat sidewise relation, then securing to the outer face of said arranged series of staves near their transverse centers thereof flexible connecting members of a length to project from each outer stave of said series, shaping said connected series of staves into a barrel body with the ends of said members disconnected, applying to said body shaped barrel removable holding means for temporarily securing it in shaped position, then securing to the outer face of said shaped barrel body in proximity to said means flexible connecting members having free end terminal portions extended from the body, and then removing said means to permit of the collapsing of the body. 85

3. A method of manufacturing a collapsible barrel body comprising the arranging of a series of barrel staves in flat sidewise relation, stapling to the outer face of said arranged series of staves near their transverse centers thereof flexible connecting members projecting from each outer stave of the series, shaping said connected series of staves into a barrel body with the ends of said members disconnected, removably mounting on said body shaped barrel body a holding means for temporarily securing it in shaped position, stapling to the outer face of said shaped barrel body outer flexible connecting members having free end terminal portions extended from the body, and then removing said holding means to permit of collapsing of the barrel body. 100

In testimony whereof, I affix my signature hereto.

ROBERT J. McCLENNY.

Certificate of Correction.

It is hereby certified that in Letters Patent No. 1,513,712, granted October 28, 1924, upon the application of Robert J. McClenney, of St. Louis, Missouri, for an improvement in "Methods of Manufacturing Collapsible Barrels," errors appear in the printed specification requiring correction as follows: Page 2, line 57, claim 1, for the word "said" read *each* and for the word "each" read *said*; line 64, same claim, strike out the words "body portion"; same page, line 81, claim 2, after the word "body" strike out the words "shaped barrel" and insert the same before the word "body," and line 100, claim 3, strike out the word "body" first occurrence; and that the said Letters Patent should be read with these corrections therein that the same may conform to the record of the case in the Patent Office.

Signed and sealed this 6th day of January, A. D. 1925.

[SEAL.]

KARL FENNING,
Acting Commissioner of Patents.
